UNITED STATES PATENT OFFICE.

LIPA POLINKOWSKY, OF LONDON, ENGLAND, ASSIGNOR TO WESTERN ELECTRIC COMPANY, INCORPORATED, OF NEW YORK, N. Y., A CORPORATION OF NEW YORK.

MACHINE-SWITCHING TELEPHONE SYSTEM.

1,386,728.

Specification of Letters Patent. Patented Aug. 9, 1921.

Application filed August 27, 1918. Serial No. 251,605.

To all whom it may concern:

Be it known that I, LIPA POLINKOWSKY, a citizen of Russia, residing at London, England, have invented certain new and useful 5 Improvements in Machine-Switching Telephone Systems, of which the following is a full, clear, concise, and exact description.

This invention relates to machine switching telephone systems, and more particularly to telephone systems in which connections are extended from a manual A board over a semi-automatic B board to the automatic switches of a distant automatic exchange or automatic satellite.

15 A feature of the invention is the provision of a semi-automatic operator's position provided with a single key set and two or more sets of registers controlled thereby, each set of registers comprising only a plurality of relays.

Another feature of the invention and one relating to the above is the provision of register sets, a plurality of which are controlled by a single set of number keys, each register set comprising a set of number relays, a set of counting relays for the impulses, a set of counting relays for the series of impulses, and means for operating one of the register sets only when the number keys are depressed.

Still another feature of the invention and one relating to the last named feature is the provision of a set of relays for connecting a trunk line to one only of the register sets upon the depression of an assignment key.

25 A further feature of this invention is an arrangement which enables the establishment of a talking-through connection over the contacts of the deenergized relays which serve for connecting the register set to the trunk, together with means to establish this circuit only after the relays have been first energized and deenergized.

Another feature of the invention is a circuit arrangement in which the trunks extended over the B-operator's position are provided with sets of relays, one set operating upon the insertion of the plug at the A-operator's position for closing the fundamental circuit and the other set operating on the depression of an assignment key for temporarily connecting the trunk with a register set, the relay set responding to the insertion of the plug on the A board being prevented from fulfilling its function unless

the set of relays which establish the temporary connection with a register set have been energized, the sets of relays being so arranged in the circuit that the last named set of relays is utilized to establish over their contacts both a temporary connection with the register set and the through-talking connection.

30 A still further feature of the invention is the provision of a set of relays associated with a trunk line and responding to the insertion of the plug on the A board for closing the fundamental circuit, and which insures that the closing of the fundamental circuit is delayed until after the plug at the A board has been fully inserted.

35 A further feature of the invention is the provision of means associated with the relay register sets for translating the numbers as set up thereon by the number keys into the system of notation used in the selecting switches of the machine switching system.

40 A particular feature of the invention and one relating to the last named feature is the provision of an improved counting relay circuit containing less than the usual number of relays and an arrangement of circuits and apparatus connected therewith for use in connection with the translation scheme of the system whereby the counting relay circuit may send an additional set of impulses on a given units selection.

45 A still further feature of the invention is the provision of means for connecting a trunk line with one only of the relay register sets, preference being given to a predetermined one of such relay register sets when both are free and the provision of means operating when both such relay register sets are taken for use to insure the complete operation of the last set taken for use whether the preferred set is maintained in use or set free.

50 A further feature of the invention is the provision of a relay register set including a set of counting relays for the impulses, a set of counting relays for the series of impulses and a set of slow operating relays brought into operation at the end of each series of impulses and controlling the length of time the fundamental circuit is kept open on the register set.

55 A particular feature of the invention and one relating to the last named feature is the arrangement of the relays of the set of slow

operating relays into slow energizing and slow deenergizing relays, in such a manner that their timely operation is made practically independent of variations in the voltage of the energizing circuit.

Figure 1 shows a cord circuit at an "A" operator's position in a manual office of the well-known type. Fig. 1^a shows a trunk line in an automatic satellite or exchange incoming from the "A" operator's position.

Figs. 2, 3 and 3^a show the keyboard, two register sets and a counting relay set at a switchless semi-automatic B operator's position to which the trunk line is connected.

In Fig. 4 is shown a group selector on the incoming end of the trunk line in an automatic satellite, located in the area of a manual telephone system, and in Fig. 4^a is shown a final selector. The same arrangement is used in an automatic exchange to establish connections from a manual board, in which case the trunk lines can be divided into groups to be selected by the B operator, and the group selector shown to the left of this figure then represents the last group selector in the exchange.

The system disclosed as embodying the present invention will be best understood from a description of the operation thereof.

When a connection extended to the manual A board is to be further extended to an automatic satellite, the A operator communicates with the semi-automatic B operator, in the well known manner, over an order wire, giving her the name of the satellite and the number wanted. The B operator gives the A operator the number of the selected free trunk to the satellite in question and depresses the assignment key 201, indicated in Fig. 1^a, individual to this trunk, which as a result is brought into connection with one of the free register sets of the B position, shown in Figs. 2 and 3, each B position being provided with a set of number keys and two equivalent register sets similarly arranged.

Only one register set, generally called the "A" register, to the right-hand of the drawing of Figs. 2 and 3, is shown in detail. The second register of the position, called the "B" register, is indicated by a few elements, which as will be seen later, have exactly the same functions as the corresponding elements shown on the A register. In order, when both register sets are free, to give privilege to one of them there is a single difference in the wiring of their circuits in that on the B register the back contact of relay 371 is connected to the front contact of the relay 372, whereas the same connection between the contacts of the corresponding relays 304 and 305 on the A register is omitted. By rearranging the wiring to open this connection on the B register and introduce it on the A register, the registers may be reversed

if desired, so that when both are free privilege is given to the B register. In the system as shown the B register can only be taken when the A register is engaged with another call. The operator, by the use of both registers, is able to set up a call on the number keys of her position during the time a previous call is in progress of selection.

Assuming both registers to be free and key 201 depressed the left-hand winding of relay 202 is energized in a circuit over the right-hand contact of key 201, common wire 220, back contact of relay 303 of the A register and back contact of relay 371 of the B register. A similar circuit over the left-hand contact of key 201 for relay 203 is attempted but is kept opened on the front contact of relay 305. Relay 202 is maintained operated in a circuit over the right-hand contact of the forced release key 204, the right-hand front contact and winding of relay 202, winding of relay 205, common wire 222, and winding of relay 304, to ground at the make-before-break contact of relay 306. Over the left-hand front contact of relay 202 the calling lamp 206 and the guarding lamp 207 are connected to an interrupter 212 and display flashing signals before the operator. The energization of relay 205 prepares, over its front contacts, the connection of the trunk line with the common leads 221 and 223 of the fundamental circuit in which the stepping relay 307 is included and which, at this time is kept open at the contact of relay 308 of the register and at contact 100 of relay 208 on the trunk line. The energization of relay 304 causes, in a circuit over its front contact, the energization of relays 303 and 309. The described circuit over the right-hand contact of key 201 is now opened at back contact of relay 303 so that at this time on the depression of the assignment key of another trunk line a connection with the registers is not possible and an erroneous depression of another assignment key during the time the number keys of the position are used for one call is without disturbing effect.

The magnetic holding means 411 of the number keys are now energized in a circuit over back contact of relay 305 and front contact of relay 309, and the number keys when depressed are, in a well known manner, magnetically held in their depressed positions.

Each register set contains a series of number relays 412, 413 and 414 corresponding to the units, 10's and 100's number keys. Since the capacity of a satellite in the arrangement shown does not exceed 2000 lines, separate number relays are not provided for the 1000's keys, and some of the counting relays, as will be shown later, are utilized to perform also the function of translation. One number relay is provided for each pair of 100's keys, and by means of a relay 311

the translation of the decimal numbers depressed on the number keys to the automatic switches arranged in a different numerical system is secured. The number keys are 5 each provided with two contacts which are utilized to control over their right-hand contacts the corresponding number relay on the A register and over their left-hand contacts the corresponding number relay of the 10 B register.

The B operator proceeds with the depression of her number keys in accordance with the numerical designation of the desired line without waiting for the A operator to 15 plug into the jack of the assigned trunk. Assuming that the number of the required line is 2222 the B operator depresses the four number keys, 415, 416, 417 and 418, in the third row from the top. Relays 412 20 and 321 are energized in a circuit over contact of key 415, wire 421, the left-hand winding of relay 321, left-hand back contact of relay 312 and right-hand front contact of relay 303. In similar circuits are energized 25 relays 413 and 322 over contact of key 416 and wire 422, and relays 414 and 323 over contact of key 417 and wire 423, whereas relay 324 is energized in a circuit containing the contact of key 418, wire 424, and the 30 right-hand back contact of relay 312. The energization of the number relays 412, 413 and 414 is maintained over their left-hand front contacts, the corresponding wires 425, 426 and 427, the front contacts of the 35 corresponding relays 321, 322 and 323 and front contact of relay 303. Over the right-hand contacts of the relays 321, 322, 323 and the left-hand contact of relay 324 a circuit is closed including relays 313, 314 and 315, 40 which are energized. This circuit leads from battery, through the winding of relay 313, front contact and left-hand armature of relay 324, right-hand armatures and front contacts of relays 321, 322 and 323, through 45 the windings of relays 314 and 315 to ground. Relay 313 provides a holding circuit for the right-hand windings of the relays 321, 322, 323 and 324, in series with the winding of relay 305, which relay is 50 energized and disconnects the magnetic clutches 411 so that the number keys are rendered free. The common test wire 224 of the B register is now connected over the front contacts of relays 305 and 309 to 55 ground so that from now on by the depression of an assignment key a trunk line can be connected to the B register. In parallel to the holding circuit described for relays 321, 322, 323 and 324 is connected the 60 winding of relay 312, which is energized, disconnects the operative windings of the above-named relays and produces over its front contact the energization of relay 308. The fundamental circuit is now prepared at 65 the contact of relay 308 and the register

is ready to control the group selector on the incoming end of the trunk shown on the left-hand side of Fig. 4. The selection cannot proceed, however, unless and until the A operator has inserted the connecting plug 70 in the jack of the assigned trunk line.

The relay 209 is energized in a circuit over left-hand contact of key 204 and the sleeve of the plug on the A operator's position. As it may happen that the B operator 75 has in the meantime already depressed the number keys and the fundamental circuit has been prepared on the register, as described, assurance is made that no closures and openings of the fundamental circuit 80 occur until the plug is fully brought into the jack, as otherwise it could happen that during the bringing in of the plug, relay 209 may, after its first energization, become deenergized for a brief interval. To secure 85 this, the energization of relay 208, which controls the closure of the fundamental circuit, occurs in a circuit over the front contact of relay 209 and the tip of the plug to ground on the cord. Relay 208 is provided 90 with make-before-break contacts and when operated disconnects its right-hand winding from the spring of the jack and connects it over the right-hand contact of relay 209, the left-hand front contact and left-hand 95 winding of relay 208, winding of relay 211 to the left-hand contact of relay 209 and ground. It may be observed that unless the assignment key 201 has been depressed to operate either of the relays 202 and 203, the 100 above traced circuit which is closed for the relay 208 by the insertion of the plug at the A operator's board is short-circuited, and relay 208 thus remains deenergized until said assignment key has been operated. This 105 short-circuit which prevents the operation of the relay 208 may be traced from battery, right-hand contact of key 204, right-hand armature and back contact of relay 202, left-hand armature and back contact of 110 relay 203 to ground over the tip of the A operator's plug in shunt of the circuit through the right-hand winding of relay 208. Relay 211 is also energized and disconnects the guarding lamp 207 so that only lamp 115 206 remains flashing, indicating to the B operator that the A operator has made the connection with the assigned trunk and the selection is progressing.

A metallic circuit is now established over 120 the two-wire trunk line 230 containing relay 501 and contacts 502 and 503 of the sequence switch 504 pertaining to the group selector, both wires of the trunk 230, the right-hand front contact of relay 208, both 125 front contacts of relay 205, common wires 221 and 223, both back contacts of relay 318, back contact of relay 319, front contact of relay 308 and winding of stepping relay 307. The energization of relay 307 causes the 130

operation of the counting relay 325, which corresponds to the operated hundreds' number relay 414 the circuit passing over back contact of relay 316, front contact of relay 5 307, left-hand back contact of relay 331, wire 428, right-hand contact of relay 414 and back contact of relay 335. Relay 325 provides a holding circuit over its winding, relay 335, front contacts of relays 325 and 10 314, back contact of relay 341 and front contact of relay 304. Relay 335 remains short-circuited over front contact of relay 307.

The energization of relay 501 provides a circuit over its front contact, contact 507 top 15 of the sequence switch, to its magnet 504. The sequence switch starts from position 1 and moves into position 2, controlled in the well known manner over its local contact 508. The magnet 510 of the trip spindle is 20 now energized in a circuit over sequence switch contact 509 top and front contact of relay 501. The trip spindle rotates and in the well known manner produces between each step the short-circuiting of relay 307 in 25 the fundamental circuit over the contacts 511, and sequence switch contact 512 bottom. When relay 307 is so deenergized relay 335 becomes energized and extends over its front contact the counting circuit to the following 30 counting relay 326, which becomes energized as soon as the short-circuiting of relay 307 is opened at the contact 511 of the trip spindle and this relay is again operated. On the last short-circuiting of the stepping relay, 35 relay 319 is operated and opens the fundamental circuit so that relay 501 is deenergized as soon as contacts 511 are opened. The trip spindle magnet 510 is now disconnected, whereas sequence switch 504, energized in a circuit over back contact of relay 40 501 and sequence switch contact 513 bottom, is started from position 2 and moved into its position 5. In leaving position 2 the trunk line 230 is disconnected on the sequence 45 switch contacts 502 and 503 bottom from relay 501 and ground respectively and connected over the same sequence switch contacts top to the left-hand windings of the repeating coil 514 and the release relay 516.

50 The supervisory relay 517 is now locally energized in a circuit over the sequence switch contact 518 bottom, and maintains the right-hand high resistance winding of relay 516 short-circuited. The power magnet 519 of 55 the brush carriage is now energized in a circuit over sequence switch contact 521 bottom and back contact of test relay 522. The power magnet moves the brush carriage in the well known manner along the terminals 60 on the row selected by the set position of the trip spindle, and the high resistance winding of test relay 523, is connected over the sequence switch contact 524 bottom, with the test brush 525, during the search for a tree 65 trunk line to a final selector.

Simultaneously with the energization of relay 319 on the register, relay 338 is also energized and causes the energization of relays 316 and 332 in a circuit over front contacts of relays 304 and 338 and right-hand 70 back contact of relay 331. Relay 332 provides over its left-hand front contact a holding circuit for its winding, but relay 331, which is connected in this circuit, being shunted by the low resistance winding of relay 316, remains deenergized. The slow operating relay 316 provides over its front contact the short-circuiting of relay 315 which when deenergized causes the operation of the slow-operating relay 317 in a circuit over 80 back contact of relay 315 and front contacts of relays 324, 305 and 309. In parallel to relay 317 is placed the left-hand winding of relay 318 which also operates. Relay 317 provides on its front contact a short-circuit 85 of relay 314 which when deenergized opens the holding circuit for the counting relays. Relay 319 again closes on its back contact the fundamental circuit. The shunt 90 placed around the winding of relay 338 secures that this relay, when deenergized, closes its back contact after all the counting relays have been deenergized. When on the front contact of relay 338 the shunt around the winding of relay 331 is opened, this relay is energized, disconnecting at its left-hand contact the counting circuit controlled by the stepping relay from the 100's number relays and connecting it over its left-hand front contact and the left-hand back contact of relay 333 and wire 429 to the 10's number relays. Relay 316 is disconnected on the 95 right-hand contact of relay 331 from relay 332 and connected to relay 334. Relay 316 when deenergized opens the short circuit 100 around relay 315, which again energizes, causing the deenergization of relay 317 and this in turn the energization of relay 314, which prepares again the holding circuit for the counting relays. 110

Relay 318 which has been energized at the particular moment described, disconnects the stepping relay from the trunk line and introduces the battery and relay 342 in the circuit of the trunk line, whereby the slow-acting relays 316 and 315 control the moment of operation of relay 318, so that the change in the circuit of the trunk line is made at this point after the sequence switch contacts 502 and 503 have changed the circuit, on the incoming end as described. Relays 516 and 342 are now energized in a metallic circuit, the first relay preventing the release of the selector and the second providing a local circuit for the second winding of relay 318 over front contact of relay 342, winding of relay 343 and front contacts of relays 324, 305 and 309. Relay 343 is energized, disconnects on its back contact the operative winding of relay 318 and main 120 125 130

tains itself operated over its front contact until the register is released.

It will be seen that relays 516 and 342 are included in a circuit in series with each other as soon as sequence switch contacts 503 and 502 are closed in position 3. At this same instant the circuit for supervisory relay 517 is also closed over sequence switch contact 518 bottom. Relay 517, by operating, short-circuits the high resistance winding of relay 516 thereby permitting both relays 342 and 516 to energize. Relay 516, by operating, closes the circuit from battery through the winding of relay 501 to ground, 10 at the armature and contact of relay 516. Relay 501 thereupon attracts its armature and opens the above traced circuit which started sequence switch 504 out of position 2 such that when said sequence switch arrives 20 in position 5 it will come to rest, and close the circuit for power magnet 519 to initiate the trunk hunting movement as above described.

When the brushes of the group selector 25 reach the terminals of a free final selector the left-hand high resistance winding of test relay 523 is energized in a circuit over sequence switch contact 524 bottom, test brush 525, contact 546 of the final selector 30 sequence switch 534 and resistance 545. Relay 523 connects, over its front contact, its low resistance winding, the winding of the 2nd test relay 522 to the 3rd brush 525 making the selector trunk line test busy in the 35 well-known manner. The high resistance release relay 547 on the final selector, which is connected in parallel to resistance 545, is thereby also energized. The energization of relay 522 causes the disconnection of the 40 power magnet 519 and also energization of sequence switch 504 in a circuit over its contact 513 bottom and front contact of relay 522. In parallel to the sequence switch is connected over its contact 507 bottom the 45 holding magnet 505 of the brush carriage, which is arrested, whereas the sequence switch starts from position 5 and moves over position 6 into position 9. On sequence switch 504 leaving position 5 relay 516 is dis- 50 connected at the sequence switch contacts 502 and 503 from the trunk line which is, in position 9, extended over the sequence switch contacts 526 top and 527 bottom, the brushes of the group selector, the sequence switch 55 contacts 531 top and 532 top to relay 533, of the final selector and to ground respectively, thus preparing the fundamental circuit on the incoming end at the final selector. In reaching position 8 the sequence switch contact 524 top connects relay 522 direct with the brush 525. The right-hand winding of relay 523 is thereby short-circuited and this relay is deenergized. When the sequence switch 504 passes position 8 relay 533 is 60 operated over the sequence switch contact

513 top and contact 508 to ground, the contact 513 being closed before and opened after contact 526 is closed. The relay 533 is thus energized in a preliminary energizing circuit closed as soon as sequence switch contacts 513 and 527 reach position 8, and due to the fact that contact 513 does not open until slightly after contact 526 closes in position 9, relay 533 is maintained energized until after the fundamental circuit is closed 75 at contact 526. This insures the operation of relay 533 under all circumstances when a connection is made with a free final selector, and, as will be shown later, secures the proper release of the switches on a premature release. 80

When the contacts 502 top, and 503 top, are opened after the sequence switch 504 leaves position 5, the relay 342 on the register is deenergized and the right-hand winding of relay 318 is opened, so that after the deenergization of this relay the fundamental circuit on the register is again closed. This takes place before sequence switch 504 reaches position 8 and the fundamental circuit is extended to the final selector. As soon as the passing contact 513 top is opened in position 9 of sequence switch 504, the stepping relay 307 is energized in the fundamental circuit, causing the energization of 90 the counting relay 326 in a circuit over back contact of relay 336, right-hand front contact of number relay 413, wire 429, back contact of relay 333, front contact of relay 331 and front contact of relay 307. Relay 100 326 prepares its holding circuit over relay 336 which remains deenergized as long as the stepping relay is operated.

Relay 533 on the final selector when energized provides a circuit for the sequence 105 switch 534 over front contact of relay 533 and sequence switch contact 535 bottom. The sequence switch starts and, controlled by its local contact 536, moves into position 2 in which the magnet of the trip spindle 110 540 is energized in a circuit over sequence switch contact 544 bottom and front contact of relay 533, and the trip spindle rotates. With each short-circuiting of the fundamental circuit at the trip spindle contacts 537 over sequence switch contact 538, the stepping relay 307 on the register is deenergized and the counting relays are operated in succession, as hereinbefore described. When relay 319 is again operated the fundamental circuit is opened and relay 533 is 115 deenergized as soon as contact 537 top is opened, the trip spindle magnet is disconnected and the sequence switch 534 is energized in a circuit over back contact of relay 533 and sequence switch contact 539 top. Sequence switch 534 moves into position 5.

In the meantime relay 338 is operated and causes the energization of relays 316 and 334. In consequence relay 315 is deener- 130

gized, relay 317 is energized and relay 314 is deenergized, and the holding circuit for the counting relays is opened. The fundamental circuit is again closed on the back contact of relay 319. The operation of relays 316, 315, 317 and 314 in succession secures such a timed control that the reclosure of the fundamental circuit is made certain before the sequence switch 534 of the final 10 reaches position 5, but only after this sequence switch leaves its position 2 and the trip spindle magnet has been disconnected on contact 544, whereby the difference in these times is selected so as to insure a safe 15 operation under all variations in the speed of the switches, voltage, etc. The four slow-acting relays 316, 315, 317 and 314 are arranged in pairs of slow-operating and slow-deenergizing relays, relays 316 and 317 being slow to energize and relays 314 and 315 slow to deenergize, in such manner that a minimum of variation in the time of their combined action is secured. If the voltage is higher and the slow-operating relay 316 20 operates quicker, the short-circuited relay 315 is deenergized slower, and vice versa. A similar relation is secured in the time of the coöperation of relays 317 and 314, it being remembered that all four relays in 25 succession control the time for the changing-over of the fundamental circuit from the 10's to the units impulses, whereas only the relays 316 and 315 control the time for changing-over the fundamental circuit after 30 the 100's impulses for the operation of the release relay 516.

After relay 338 is again deenergized relay 334 is maintained operated over winding of relay 333 and front contact of relay 334. 40 Relay 333 is now energized, disconnects on its left-hand contact the circuit controlling the counting relays from wire 429 and prepares a new controlling circuit over wire 430, so that as soon as relay 316 has made 45 its back contact, relay 326 is energized in a circuit over back contact of relay 336, front contact of relay 412, wire 430, back contact of relay 344, front contact of relays 333, 331 and 307, and back contact of relay 316.

When the sequence switch 534 reaches its position 5 it remains in such position since, as has been explained, the fundamental circuit is again closed prior to this time, and 55 relay 533 energized to open the circuit which drove sequence switch 534 out of position 2 and the power magnet 550 which controls the movement of the brush carriage is energized in a circuit over front contact of relay 533 and sequence switch contact 541 top, and the brush carriage is moved in the well-known manner along the third terminal row, short-circuitings of the stepping relay 307 in the fundamental circuit being 60 again produced at contact 542 top of the 65

brush carriage and the counting relays on the register are operated a third time under the control of the stepping relay. When relay 319 is again energized the fundamental circuit is opened, and as soon as contact 70 542 is also opened relay 533 is deenergized, the power magnet 550 is disconnected and the sequence switch 534 is again energized and moves from its position 5 into its position 10. The holding magnet 560 which is 75 now connected in parallel to the sequence switch over contact 543 bottom, is also energized and the brush carriage is arrested with the brushes on the wanted line. After the sequence switch 534 leaves position 5 80 the resistance 545 is disconnected at contact 546 and relay 522 at the group selector is deenergized. The sequence switch 504 is thereby energized in a circuit over back contact of relay 522 and sequence switch contact 521 85 top, and moves into its position 14. After leaving position 9 the metallic through connection to the final selector is opened on the sequence switch contacts 526 and 527, and in position 12 the corresponding brushes of 90 the selector are connected over the same sequence switch contacts with the transmitter battery supply over the right-hand windings of the repeating coil 514 and the supervisory relay 517. The release relay 516 and the 95 left-hand windings of the repeating coil are again brought into connection with the trunk line over sequence switch contacts 502 and 503.

In the meantime the last energization of 100 relay 338 on the register causes the energization of relays 316 and 306 in a circuit over the right-hand front contacts of relays 331 and 333. The holding circuit for the relays 304, 205 and 202 is thereby maintained over 105 the left front contact of relay 306, front contact of relay 314, back contact of relay 341 and front contact of relay 304. The make-before-break relay 306 provides a locking circuit for its right-hand winding 110 over its right-hand front contact and front contact of relay 303. The opening of the holding circuit for the counting relays is again controlled through the operation of the relays 316, 315, 317 and 314 in succession. The opening of the circuit which contains relays 304, 205 and 202 takes place at 115 the same moment. Relay 205 when deenergized disconnects the trunk line from the common leads 221 and 223 and provides a through connection of the trunk lines over both its back contacts and both back contacts of relay 213 with the tip and the ring of the connecting plug, whereby the moment of this through connection is again regulated by the timing relays 316, 315, 317 and 314, so that the through connection takes 120 place after relay 533 on the final selector has been disconnected on the sequence switch contact 531 from the trunk but before the 125 130

sequence switch 504 of the group selector has reached position 14. Relay 516 is now energized in a metallic circuit containing the battery and supervisory relay in the cord 5 of the A operator's position, and prevents the release of the group selector. The de-energization of relay 202 causes the lighting of lamp 206 in a circuit over left-hand back contact of relay 202, right-hand back 10 contact of relay 203, and left-hand front contact of relay 209. The right-hand winding of relay 208 is now short-circuited over the other back contacts of relays 203 and 202, but the left-hand winding of relay 15 208 remains energized in the circuit previously described and maintains the operation of this relay for the duration of the connection. The de-energization of relay 304 causes the release of all holding circuits 20 on the A register. Relay 303 being de-energized again prepares on its back contact the test circuit for the trunks to the A register which can now be used for a new call provided either that the B register 25 is free and its relay 371 de-energized, or that the B register is busy but its relays 372 and 373 are energized after the number has been set up on the keys for the trunk connected with the B register.

30 When the sequence switch 534 of the final selector reaches position 8, the wanted line is tested and if found free the right-hand high resistance winding of test relay 551 is energized in a circuit over the cut-off relay 35 552 of the wanted line, the test brush 553 and the sequence switch contact 554. The left-hand low resistance winding of the test relay 551 and the 2nd test relay 548 are brought into circuit in parallel to the high 40 resistance winding of relay 551 and the wanted line is made busy. When reaching position 10, the magnet of sequence switch 534 is maintained energized in a circuit over back contact of relay 533, front contact 45 of relay 548 and sequence switch contact 539 bottom, and moves over positions 10 and 11. In position 12 an alternating ringing current is immediately sent to the station of the wanted line in a circuit over the sequence switch contacts 555 and 556 and the 50 ringing relay 557. Relay 533 is connected over sequence switch contact 558 with a common interrupter 559, which, when closed, causes the energization of relay 533 55 and, in consequence, the sequence switch 534, over a circuit including front contact of relay 533 and sequence switch contact 535 bottom, which sequence switch moves into its position 13 in which relay 533 is connected 60 over contact 531 bottom, with a further common interrupter 561. The two interrupters 559 and 561 are continually operated and are arranged to close for a short time the circuit to ground at pre-determined 65 time intervals, so that after the sequence

switch 534 reaches position 12, it is brought, after the lapse of a few seconds, over its positions 12 and 13 into position 14. The duration of time in which sequence switch 534 remains in these positions and an instantaneou 70 s ring is sent to the wanted station depends upon the moment the sequence switch reaches position 12 and slightly varies according to whether at this moment the interrupter 559 has just passed 75 its contact or is near to it. The contact on these interrupters is closed for a short time sufficient to energize relay 533 and in consequence the sequence switch 534 but not sufficient to maintain its energization for more 80 than to move the sequence switch over one position. In this manner the sequence switch 534 is at least held in position 13 for the time which elapses between the closure of the interrupters 559 and 561. After se- 85 quence switch 534 reaches position 14, the direct connection of the ringing current is removed by the opening of sequence switch contact 555, and the connection with the source of ringing current is now maintained 90 with the line over sequence switch contact 562 and the interrupter 563, which, in selected time intervals, connects periodically either the ringing current or ground to the line. As soon as the receiver at the wanted 95 station is lifted from the hook, the ringing relay 557 is energized and causes, over its front contact and sequence switch contact 535, the energization of sequence switch 534, which starts from position 14 and moves 100 into its position 15 in which the ringing current is disconnected from the line which is now through connected over sequence switch contacts 562 and 556 to the transmitter current supply at the group selec- 105 tor. Relay 517 is energized and in short-circuiting the high-resistance winding of relay 516 transfers the supervision to the supervisory relay on the cord on the A operator's position.

If instead of calling an even thousand, a number is required in which the 1000's digit is odd, the following change in the operation of the register on the semi-automatic B operator's position takes place. Assuming 110 that the wanted number was 1222, instead of depressing the number key 418, the operator would have then depressed the number key 419. The circuit for the left-hand winding of relay 324, in this case, is established 115 over back contact of relay 337 and winding of the counting relay 327, which relay operates and provides a holding circuit for its winding over the winding of relay 337, but relay 337 remains for the present deenergized, being short-circuited by the low resistance winding of relay 324. When, as 120 has been described, the number keys are released and the operative winding of relay 324 is opened on the right-hand contact of 125 130

relay 312, relay 337 becomes energized. It is therefore evident that when the first setting up of the counting relays, as described, proceeds, one counting relay less needs now 5 to be operated and the number of steps the trip spindle of the group selector will complete under the control of the 100's number relays is now reduced by one and the trip spindle will be arrested to release the 10 brushes of an odd level.

If for example the wanted number depressed on the number keys was 2322, key 420 is depressed instead of key 417. The 15 same relay 414 is operated, as described before, but its circuit is now extended over the left-hand winding of relay 311 which when energized, provides a holding circuit over its right-hand winding and the left-hand winding of relay 344 over the front contact 20 of relay 311, back contact of relay 341, to the front contact of relay 304. After the second series of impulses is completed as described, and relay 333 is operated, the units impulses are not extended over wire 430 25 to the contact of the energized units number relay 412, but are directed over the left-hand front contact of relay 344 direct to the 1st counting relay on the right of Fig. 3^a. The brush carriage of the final when 30 rotating, makes a series of eleven short-circuitings until all the counting relays to the left of the one initially energized are operated and the brush carriage moves thereby over all the terminals of the first 35 hundred and to the terminals of the second hundred. During the time the final selector brush carriage is making the comparatively long step between the first and second half of the terminal row, the following operations 40 take place on the relays of the register. The operation of relay 319 remains without influence on the fundamental circuit since relay 307 remains short-circuited at the final selector. On the other hand the operation 45 of relay 338 causes the energization of relay 345 in a circuit over front contacts of relays 338, 331, 333 and 344 and right-hand winding of 344. Relay 316 which is in the same circuit, starts to energize, but, as will be 50 seen later, it is disconnected before the series of the timing relays can affect the fundamental circuit. Relay 345 over its front contact provides for the energization of relay 341, which opens at its back contact 55 the circuit for the holding winding of relay 311, and as this circuit is also opened on the back contact of relay 338, relay 311 is deenergized. The holding circuit of the counting relays is thereby also opened at 60 back contact of relay 341. All counting relays are now deenergized. As has been previously mentioned, relay 338 makes its back contact after all other counting relays have left their front contact so that when the 65 first mentioned contact is closed, none of

the counting relays could remain locked up. At the moment relay 338 closes its back contact, the counting relay 326 is again energized in a circuit over contact of relay 336, front contact of relay 412, wire 430, front contact of relay 341, back contact of relay 338, and front contact of relay 304. In the meantime through the opening of the front contact on relay 333, relay 345 and, in consequence, relay 341 begin to 75 deenergize. These relays are so timed that relay 341 leaves its front contact after it has been assured that the counting relay 326 has made its front contact and has locked itself up with its corresponding relay 80 336, which is energized as soon as relay 341 opens its front contact. The described series of operations of the relays of the register takes place before the short-circuiting contact on the brush carriage of the final selector has been opened. Further impulses produced in the fundamental circuit on the final selector are now transferred to counting relays of the register over wire 430 and back contact of relay 344, as has been described, and when relay 319 is again operated, the fundamental circuit is finally opened, whereas the energization of relay 338 provides the disconnection of the register and the through connection of the trunk, as has been described. The eleventh short-circuiting of the fundamental circuit has been utilized for the first deenergization of the counting relay, and the continuation of the short-circuiting in the second half of the 95 terminal row would bring the final selector one step too far, were it not that this has been avoided through the local energization of the first counting relay for the second half of the impulse series as described. 100

105 After the conversation is completed and the clearing out lamps have been displayed on the A operator's position, she is able to break down the connection by withdrawing the plugs from the jacks of the calling line and the trunk line. This causes the release of the automatic switches in the satellite and the restoration of the relays on the outgoing end of the trunk to their position of rest without the aid of the semi-B operator. After the plug is withdrawn from the jack, relay 209 is deenergized and opens at its front contacts the holding circuit of relays 110 208 and 211. Relay 516 is also deenergized and in consequence relay 501. On the energization of sequence switch 504 in a circuit over back contact of relay 501 and sequence switch contact 513 bottom, the sequence switch 504 is started from position 115 14 and moved into its position 17. In leaving position 14 the brushes are isolated at the corresponding sequence switch contacts 524, 527 and 526, and the release of the final selector is started. When the sequence switch 504 reaches position 17, the power 120 125 130

magnet 519 is again energized in a circuit over sequence switch contact 521 bottom and back contact of relay 522, and the group selector brush carriage is moved into its home 5 position, on reaching which relay 522 is energized in a circuit over home contact 520 of the brush carriage and sequence switch contact 518 top. The power magnet 519 is disconnected and the sequence switch 504 10 and holding magnet 505 are energized in a circuit over the front contact of relay 522. The brush carriage is arrested and the sequence switch 504 starts from position 17 and moves into position 1. The restoration 15 of the trip spindle has already taken place after the brush carriage has been set in a circuit over sequence switch contact 509 bottom and contact 511 bottom of the trip spindle, as soon as the sequence switch 504 20 reached position 8.

When the test brush 525 is isolated as just described, relay 547 becomes deenergized and sequence switch 534 is energized in a circuit over its contact 543 top and the 25 back contact of relay 547. The sequence switch 534 starts from position 15 and moves into position 17 in which relay 533 is brought into connection with the wanted line over sequence switch contacts 555, 556 30 and 532. As the called subscriber has restored his receiver, and the called line is opened to direct current relay 533 remains deenergized and the sequence switch 534 is maintained energized over back contact of 35 relay 538 and moves over position 17 into position 18 in which the power magnet 550 is again energized in a circuit over the back contacts of relays 533 and 548 and sequence switch contact 541 bottom. The brush carriage 40 is moved to its position of rest and, on reaching its home contact, relay 533 is energized in a circuit over sequence switch contact 558 top and home contact of brush carriage 542 bottom. The power magnet of 45 the brush carriage is disconnected whereas the sequence switch 534 together with the holding magnet 560 is again energized in a circuit over front contact of relay 533, as described. The brush carriage is arrested 50 and sequence switch 534 starts from position 18 and moves into its position 1. The restoration of the trip spindle has been already effected over sequence switch contact 544 top and trip spindle contact 537 bottom 55 when the sequence switch 534 reached position 12.

If after the release of a connection the trunk is immediately assigned for a new call and assuming that the B operator would be 60 able to complete the assignment of the trunk and the depression of the number keys before the brush carriage of the group selector and its sequence switch have returned to their position of rest, the fundamental circuit is maintained opened on the contacts 65

502 and 503 of the sequence switch 504 and the register is kept waiting until these contacts are closed in position 1 of sequence switch 504.

If the wanted line has been found busy 70 and during the time sequence switch 534 passes position 8 relay 551 does not become energized, the sequence switch 534 is arrested in position 10 in which the operative winding of relay 551 is disconnected at sequence switch contact 554. The secondary winding of the common tone coil 568 is brought in bridge to the line over sequence switch contacts 567 and 565 and a busy tone 75 is given to the calling subscriber. The interrupter 564 produces also in the well known manner a busy flash signal on the called supervisory lamp at the A operator's position. After the A operator withdraws the outgoing plug, the release of the group 80 selector proceeds in the manner described. When as a result relay 547 becomes deenergized sequence switch 534 starts from position 10 and is arrested in position 11, in which the power magnet of the brush carriage 85 550 is energized in a circuit over contact 541 bottom as described and the brush carriage is moved into its home position with the brushes opened. In reaching the home position relay 533 is operated over 90 home contact 542 as described and sequence switch 534 is again energized and started from position 11. In positions 12 to 16 the sequence switch 534 is now maintained energized over back contact of relay 547, in 95 position 17 over back contact of relay 533 and in position 18 over front contact of relay 533. The sequence switch 534 therefore moves directly into position 1.

Disconnection however can take place at 100 any moment desirable during the progress of the selection, either through withdrawing the plug from the jack of the trunk line as described, or through the use of forced release key 204 provided on each trunk on the 105 B operator's position. If the B operator, for example, notices before the selection is completed that she has made a mistake, she depresses the key 204 and opens on its right-hand contact the holding circuit for relays 110 202, 205 and 304, if the connection has been made with the A register, or the holding circuit of relays 203, 213 and 371 if the connection has been made with the B register. At the left-hand contact of key 204 is opened 115 the circuit for relay 209, which in turn opens the circuit for relay 208. The relays on the register and on the outgoing end of the trunk line are therefore restored to their condition of rest, and in depressing the assignment key a second time the operator can repeat the call.

If a premature release happens during 120 the time the group selector is searching the terminals for a free final selector, relay 516 125 130

will thereby become deenergized and in consequence also relay 501. Sequence switch 504 is then energized and starts immediately from its position 5. In position 6 relay 501 is locally energized over sequence switch contact 512 top, whereas the power magnet 519 is energized over contact 521 bottom and back contact of relay 522. The brush carriage is restored to its position of rest, while its brushes are kept opened on the corresponding sequence switch contacts 524, 527 and 526. Should the premature release happen at the moment the test relay 523 has been operated over the terminal of 15 a free final selector, and the sequence switch 504 begins to extend the fundamental circuit to the final selector sequence switch 534 would not be moved out from its position of rest since the fundamental circuit could not 20 be again closed on the outgoing end of the trunk line. Under these special circumstances the group selector would be maintained out of service connected to a final selector. To avoid this, the final selector 25 always receives a starting impulse over passing contact 513 top, as has been described, and if, after sequence switch 534 leaves position 1 relay 533 is not energized, this sequence switch moves over positions 2 and 5 30 and in opening contact 546 causes the deenergization of relay 522 and the release of the group selector. The sequence switch of the group selector will therefore pass its position 14 before the sequence switch of the 35 final selector, which is moving with a lower speed, reaches position 11. In passing positions 8 and 9 relay 533 will be energized over sequence switch contact 558 top, and the home contact 542 and the power magnet 40 550 will receive a start and move the final selector brush carriage from its home position only to restore it again in position 11 of the sequence switch, so securing a new centering of the brush carriage against its 45 home contact. The starting of the brush carriage on a final selector during a premature release is especially useful if the fundamental circuit is opened at the moment the brush carriage has started in position 5 of 50 the sequence switch, as has been described, and did not have time to move away from its home contact, whereby the brushes may happen to stop in line with the trip spindle, and more than one brush set would be released 55 during the restoration of the trip spindle in position 12 of the sequence switch.

If the A operator plugs into the jack of the trunk before the B operator has depressed the assignment key, only relay 209 is 60 energized, whereas the energization of relay 208 and consequently the through connection to the selector is prevented through the short-circuiting of the winding of relay 208 over the back contacts of relays 203 and 202, 65 and the right-hand contact of key 204.

The following signals are displayed from time to time before the B operator to indicate the different conditions of the trunk line, both lamps 207 and 206 light in a circuit over the front contact of relay 209, right-hand back contact of relay 205 and left-hand contact of relay 202 if the A operator plugs into a trunk line which has not been assigned. Both lamps 212 and 206 show a flash signal if the assignment key is depressed but the A operator has not plugged into the jack. Lamp 206 flashing and lamp 212 extinguished indicates the progress of the selection. The lamp 206 lighted and 75 212 extinguished indicates that the trunk line on an established connection, and both lamps extinguished indicates the condition of rest. In addition to these lamps individual to the trunk line there are provided register progress lamps 364, 365 and 366 for 80 the 100's, 10's, and units impulses, and in observing them a delay in the progress of the selection can be easily noticed and the freeing of the register may be accomplished if desired by depressing key 204, as 85 described.

What is claimed is:

1. In a telephone exchange system, a plurality of lines, means including a connecting circuit and a selectively operable switching device for interconnecting two of said lines, an operator's key board; a plurality of register sets each comprising a set of number relays, a set of counting relays and a set of switching relays; means under the control of 95 said key-board for variably operating the number relays of any one of said plurality of register sets, means jointly controlled by said switching device and the operated number relays for variably operating the associated counting relays, means controlled by the counting relays for operating the associated switching relays, and means for restricting the control of said key-board to the number relays of one register set at a time. 100

2. In a telephone exchange system, a plurality of lines, means including a connecting circuit and a selectively operable switching device for interconnecting two of said lines, an operator's key-board; a plurality of register sets each comprising a set of number relays, a set of counting relays and a set of switching relays; means under the control of 115 said key-board for variably operating the number relays of any one of said plurality of register sets, means jointly controlled by said switching device and the operated number relays for variably operating the associated counting relays, means controlled by the counting relays for operating the associated switching relays, and means for associating with said connecting circuit only one 120 register set at a time. 125

3. In a telephone exchange system, a plurality of lines, means including a connecting 130

- 5 circuit and a selectively operable switching device for interconnecting two of said lines, an operator's key-board; a plurality of register sets each comprising a set of number 70 relays, a set of counting relays and a set of switching relays; means under the control of said key-board for variably operating the number relays of any one of said plurality of register sets, means jointly controlled by 75 said circuit.
- 10 6. In a telephone exchange system, a plurality of lines, a plurality of selectively operable switching devices for interconnecting two of said lines, a sender for controlling the operation of said devices, a relay for co-operating in the control of one of said devices, a controlling switch for another of said devices, an energizing circuit for said relay, means operated by said switch during its controlling operation for closing and then opening said energizing circuit, a second circuit for said relay including a contact at said 80 sender, and means operated by said switch for closing said second circuit prior to the opening of the first mentioned energizing circuit.
- 15 7. In a telephone exchange system, a plurality of lines, a plurality of selectively operable switching devices for interconnecting two of said lines, a sender for controlling the operation of said devices, a relay for co-operating in the control of one of said devices, an energizing circuit for said relay, means under the sole control of said one of said devices and another one of said devices for closing said energizing circuit, another energizing circuit for said relay, and a contact at 85 said sender for closing said last mentioned circuit.
- 20 8. In a telephone exchange system, a plurality of lines, means including a switching device for interconnecting two of said lines, means including a controlling device for causing said switching device to perform two selective operations in succession, means for variably operating said controlling device in successive stages, a controlling circuit between said controlling device and said switching device, and a slow-to-energize and a slow-to-deenergize relay for controlling said circuit.
- 25 9. In a telephone exchange system, a plurality of lines, means including a switching device for interconnecting two of said lines, means including a controlling device for causing said switching device to perform two selective operations in succession, means for variably operating said controlling device in successive stages, a controlling circuit between said controlling device and said switching device, a slow-to-deenergize relay for controlling said circuit, and a slow-to-energize relay for controlling said relay.
- 30 10. In a telephone exchange system, a plurality of lines, means including a plurality of switching devices for interconnecting calling and called lines, a sender for controlling the operation of said switches in accordance with the numerical designation of the called line, switching means for causing said sender to control the switching devices in accordance with the successive digits of the called number, and a slow-to-energize and a slow-to-deenergize relay for controlling the operation of said switching 100 means.
- 35 11. In a telephone exchange system, a plurality of lines, a selectively operable switching device for interconnecting two of said lines, electromagnetic operating means for 105 said device, an operator's position, a circuit extending from said position toward said electromagnetic operating means, a keyboard and a set of counting relays at said position, means controlled by said switching device 110 during its operation for causing the gradual operation of all of said counting relays, means controlled by the keys of said board for determining the number of the counting relays to be actuated, and means at said position for delaying the operation of the last mentioned means until the said means controlled by the switching device has operated 115 all of said counting relays.
- 40 12. In a telephone exchange system, a plurality of lines, means including a switching device for interconnecting two of said lines,

rality of lines, a selectively operable switching device for interconnecting two of said lines, electromagnetic operating means for said device, an operator's position, a circuit 5 extending from said position toward said operating means, a keyboard and a set of counting relays at said position, means controlled by said switching device during its operation for causing the gradual operation 10 of all of said counting relays, means controlled by the keys of said board for determining the number of the counting relays to be actuated, means at said position for delaying the operation of the last mentioned 15 means until the said means controlled by the switching device has operated all of said counting relays, and a relay operable through a certain key of said board for controlling the actuation of said last mentioned 20 means.

13. In a telephone exchange system, a selectively operable switching device, a set of counting relays for controlling the operation of said device, energizing and locking circuits for said relays, means operative upon the actuation of a certain one of said counting relays for opening said locking circuits, means for preventing the operation of said means, and separate means for opening said 30 locking circuits.

14. In a telephone exchange system, a plurality of selectively operable switching devices, a set of counting relays for controlling the operation of said devices, energizing and locking circuits for said relays, means actuated upon the operation of one of said relays in controlling one of said switching devices for opening said locking circuits, change-over means operated upon 40 the opening of said locking circuits for causing said relays to control another one of said devices, separate means for opening said locking circuits, and means controlled by said separate means for preventing the 45 operation of said change-over means.

15. In a telephone exchange system, subscribers' lines, a connecting circuit, automatic switches for extending said circuit to interconnect said lines, a controlling 50 mechanism for governing the movement of said switches, and a set of relays operative to associate said controlling mechanism with the automatic switches and also serving to complete said connecting circuit, said 55 relays being effective to complete the connecting circuit only after having operated to associate the controlling mechanism with the automatic switches.

16. In a telephone exchange system, subscribers' lines, a connecting circuit, automatic switches for extending said circuit to interconnect said lines, a plurality of impulse controlling mechanisms for governing the movement of said switches, and a set of 65 relays operative to associate an idle one

of such mechanisms with said automatic switches and also serving to subsequently complete said connecting circuit, said relays being effective to complete the connecting circuit only after having operated to associate a controlling mechanism with the automatic switches. 70

17. In a telephone exchange system, subscribers' lines, a connecting circuit, means including automatic switches for extending 75 said connecting circuit to establish a connection between the subscribers' lines, a controlling mechanism for governing the movement of said switches, and a set of relays operative to associate said controlling mechanism 80 with the connecting circuit and also serving to complete the connecting circuit, said relays being effective to complete the connecting circuit only after having operated to associate the controlling mechanism 85 with said connecting circuit.

18. In a telephone exchange system, subscribers' lines, a connecting circuit, means including automatic switches for extending said connecting circuit to establish a connection between said lines, a plurality of controlling mechanisms for governing the movement of said automatic switches, and a set of connecting relays operative to associate one of said mechanisms with the connecting circuit and also serving to complete 90 said connecting circuit, said connecting relays being effective to complete the connecting circuit only after having operated to associate a controlling mechanism therewith. 95

19. In a telephone exchange system, subscribers' lines, a connecting circuit, automatic switches for extending said connecting circuit to interconnect the subscribers' lines, a plurality of controlling mechanisms 105 for governing the movement of the automatic switches, said mechanisms being arranged to be taken for use in a definite order, and a set of connecting relays operative to associate an idle one of said mechanisms with said connecting circuit and also serving to complete the connecting circuit, said relays being effective to complete the connecting circuit only after having associated a controlling mechanism therewith. 110

20. In a telephone exchange system, subscribers' lines, a connecting circuit, automatic switches for extending said circuit to interconnect said lines, a controlling mechanism for governing the movement of said 120 automatic switches, and a relay operative to associate said mechanism with the automatic switches and also serving to complete the connecting circuit, said relay being effective to complete said connecting circuit only after having been energized and deenergized. 125

21. In a telephone exchange system, subscribers' lines, a connecting circuit, switches for extending said circuit to interconnect 130

said lines, a controlling mechanism, and a relay operative when energized to connect said mechanism to the connecting circuit to control said switches and operative when deenergized to complete said connecting circuit, said relay being effective to complete the connecting circuit only after having been first energized and deenergized.

22. In a telephone exchange system, subscribers' lines, a trunk circuit, switches for extending said trunk to interconnect said lines, an operator's position, a switch controlling mechanism at said position, means under the control of the operator for variably setting said mechanism, and a relay arranged when energized to connect the controlling mechanism with said trunk to control the operation of said switches and arranged when deenergized to complete said trunk circuit for conversation, said relay being effective to complete the trunk circuit only after having been energized and subsequently deenergized.

23. In a telephone system, an exchange, subscribers' lines terminating therein, a second exchange, subscribers' lines terminating therein, a trunk circuit between said exchanges, means for connecting a calling line in the first exchange to said trunk, automatic switches in the second exchange for extending said trunk to a called line, impulse control mechanism at said first exchange, and a set of relays operative to associate said mechanism with the trunk to control the operation of said switches and also operative to complete said trunk circuit for conversation, said relays being effective to complete said trunk circuit only after having first connected the controlling mechanism therewith.

24. In a telephone exchange system, subscribers' lines, an A operator's position, a trunk circuit, a cord circuit at the A operator's position for extending a line to said trunk, automatic switches for extending said trunk, a B operator's position, a controlling mechanism, a set of relays operated under the control of the B operator to connect said mechanism to said trunk to establish a controlling circuit for said switches, and a second set of relays operative to complete the switch controlling circuit and controlled jointly by the operation of said first set of relays and the insertion of the plug of the A operator's cord circuit in the jack of said trunk.

25. In a telephone exchange system, sub-

scribers' lines, an A operator's position, a trunk circuit, a cord circuit at the A operator's position for connecting a calling line to said trunk, selective switches for extending said trunk, a B operator's position, a controlling mechanism, a set of relays operated under the control of the B operator for connecting said mechanism to the trunk to prepare a controlling circuit for said switches, and a second set of relays for completing said switch controlling circuit and operated only when said first set of relays are operated and the plug of the A operator's cord is fully inserted in the jack of said trunk circuit.

26. In a telephone exchange system, subscribers' lines, an A operator's position, a trunk circuit, a cord circuit at the A operator's position for connecting a calling line to said trunk, selective switches for extending said trunk, a B operator's position, a controlling mechanism, a set of relays operated under the control of the B operator for connecting said mechanism to the trunk to prepare a controlling circuit for said switches, and a second set of relays for completing said switch controlling circuit and operated only when said first set of relays are operated and the plug of the A operator's cord is fully inserted in the jack of said trunk circuit, both of said sets of relays serving to complete said trunk circuit for conversation after the selective switches have been operated.

27. In a telephone exchange system, subscribers' lines, an A operator's position, a trunk circuit, a cord circuit at the A operator's position for connecting a calling line to said trunk, selective switches for extending said trunk, a B operator's position, a controlling mechanism, a set of relays operated under the control of the B operator for connecting said mechanism to the trunk to prepare a controlling circuit for said switches, and a second set of relays for completing said switch controlling circuit and operated only when said first set of relays are operated and the plug of the A operator's cord is fully inserted in the jack of said trunk circuit, said first set of relays being arranged to deenergize after said switches have been operated and complete the trunk circuit for conversation.

In witness whereof, I hereunto subscribe my name this 11 day of July A. D., 1918.

LIPA POLINKOWSKY.
